CAN

Edgar F. Dival, Western Springs, Ill., assignor to
International Patents Development Company,
Wilmington, Del., a corporation of Delaware

Original application November 28, 1932, Serial No.
644,674. Divided and this application February
2, 1934, Serial No. 709,464

4 Claims. (Cl. 221—23)

This invention relates to cans or like receptacles having openings adapted to be closed by discs or plugs held in place by friction.

One of the objects of the invention is to provide a can of this type with a pouring spout to facilitate the discharge of the contents of the can. A can so constructed may be used, for example, as a jug or pitcher.

Another object of the invention is to provide for a can having a spout of this sort of arrangement whereby the can in shipment may be closed by the ordinary friction disc or plug, for which the spout assembly may be substituted when the contents of the can are to be used.

15 A further object of the invention is to provide a cover for the spout, which besides serving as a dust cap during intervals of use, will protect the spout from injury, and will also strengthen and rigidify the can top when cans of this sort are packed for shipment.

This application is a division of my copending application Serial No. 644,674, filed November 28, 1932.

The invention is illustrated in certain preferred embodiments in the accompanying drawing, wherein

Fig. 1 is a view in perspective of the upper part of a can provided with one of the closure and spout arrangements contemplated by the invention.

Fig. 2 is a vertical sectional view through the spout and can top assembly showing the parts when the can is shipped, the spout being provided with a dust cap as contemplated by the invention.

Fig. 3 is a vertical sectional view showing the imperforate closure removed and the spouted closure in place in the can head.

Fig. 4 is a vertical sectional view of the can closed by the ordinary imperforate closure, used when the can is shipped, this figure also showing the spout closure and dust cap assembly which is substituted for the imperforate closure when the contents of the can are to be used; the spout closure being in this case sent separately and not nested with the imperforate closure as in the arrangement of Figs. 1 to 3.

Fig. 5 is a view in perspective of the dust cap.

Referring first to Figs. 1 to 3, 24 designates a can top consisting of a cover plate 25 having an opening, preferably eccentrically arranged, surrounded by a friction ring 26 in the form of a downturned flange, and an imperforate closure disc 27 formed with an upturned flange 28 providing a friction surface adapted to fit into said

friction ring. Into the imperforate friction disc 27 is fitted a disc or spout supporting member 29 formed with a pouring opening 30, the upper edge of the spout supporting member 29 being preferably turned over to form a stop bead 31. Secured to the spout supporting member 29 in relation to the opening 30 is a spout 32, the pouring end 33 of which extends to or preferably slightly beyond, the edge of the can. The spout supporting member 29 to which the spout is secured is provided with two friction surfaces. The lower surface, 34 is adapted to fit into the disc 27, as shown in Figs. 1 and 2, for convenience in securing the spout supporting member 29 to the can top during shipment or storage. The upper friction surface 35 is of slightly larger diameter so as to fit the friction ring 26, as shown in Fig. 3, when the imperforate disc 27 is removed by the consumer.

Covering the spout 32 and supported by the upper edges thereof is a cover or dust cap 36 formed with a flange 37, the edge of which is turned over to form a bead 38 and which is adapted to bear against the portion of the bead 31 of spout supporting member 29 which is nearest the edge of the can; the flange being preferably widened in the direction toward the pouring end of the spout, as shown.

A somewhat different arrangement is illustrated in Fig. 4. The can in this case is shipped to the customer, closed by the imperforate disc or plug 39, which is of common construction. The customer is also sent the spout section shown in the upper part of the figure, consisting of a spout supporting member 40 of the friction disc type formed with a bead 41 and provided with a spout 42 and a dust cap 43. The spout and dust cap are of the same construction as shown in and as above described in connection with Figs. 2 and 3, the dust cover 43 having a flange 44 which bears at its forward edge against a portion of the bead 41.

In order to prevent dripping, especially when the can contains oil, it is essential to maintain a proper distance between the lip of the spout and the edge of the can.

Where the cans are packed in crates or cartons and the packages are piled one above the other, as customary in storage or shipment, the spouts are likely to be bent out of line. The can tops themselves are sometimes bent. By forming the dust cap so that it bears against the bead 31 of the spout supporting member 29 (or the bead 41 of the disc 40, Fig. 4) the weight on the dust cover is not borne by the pouring end of the spout but is uniformly transmitted to the top of the

can so that both spout and can top are prevented from being bent.

It is understood that the form of the invention herein shown and described should be taken 5 merely as an illustration of the same and that various changes in the shape, size and arrangement of the parts may be resorted to, without departing from the spirit of my invention, or from the scope of the following claims.

10 I claim:

1. In combination with a can, the top of which is formed with an opening surrounded by a friction ring, an imperforate disc closure having a friction surface to fit into said friction ring, and a spout supporting member provided with a spout formed with a lower friction surface to fit into said imperforate disc closure, and an upper friction surface of larger diameter adapted to fit the friction ring on the can body when the imperforate disc closure is removed.

2. In combination with a can, the top of which is formed with an opening surrounded by a friction ring, a spout supporting member comprising a disc provided with a friction surface to fit said friction ring, said disc being formed with a bead above said friction surface, a spout secured to said disc and a cover for said spout having a

depending flange formed so a portion thereof bears on said bead.

3. In combination with a can, the top of which is formed with an opening surrounded by a friction ring, a spout supporting member having a friction surface to fit said friction ring, a bead on the upper portion of said spout supporting member, a spout secured to said spout supporting member, and a cover for said spout having a depending flange so formed that a portion thereof 10 bears on said bead.

4. In combination with a can within the top of which is formed an eccentrically arranged opening surrounded by a friction ring, a spout supporting member formed with a friction surface to fit said opening and a stop bead above said friction surface, said spout supporting member having an eccentrically arranged opening surrounded by a flange projecting above the spout supporting member, a spout rigidly and non-rotatably secured to said disc by means of said flange, said spout extending outwardly to, without projecting substantially beyond, a point in vertical alignment with the edge of the can top, and a downturned pouring lip formed on the 20 25 outer end of said spout.

EDGAR F. DIVAL.
